US00D732361S

(12) **United States Design Patent**
Dyer

(10) **Patent No.:** **US D732,361 S**
(45) **Date of Patent:** **** Jun. 23, 2015**

(54) **CABLE TIE TENSIONING AND CUT-OFF
TOOL HANDLE**

RE29,973 E 4/1979 Paradis
4,165,816 A 8/1979 Tupper
4,168,012 A 9/1979 Hawkinson
4,192,358 A 3/1980 Bone

(71) Applicant: **Edward P. Dyer**, Germantown, WI (US)

FIG. 1 is a left side perspective view of the cable tie tensioning and cut-off tool handle;

FIG. 2 is a right side perspective view of the cable tie tensioning and cut-off tool handle;

FIG. 3 is a left side elevation view;

FIG. 4 is a right side elevation view;

FIG. 5 is a top plan view thereof;

FIG. 6 is a front elevation view thereof; and,

FIG. 7 is a rear elevation view thereof.

The broken lines in the drawings illustrate features and linear detail that form no part of the claim.
